UNITED STATES PATENT OFFICE.

KATHERINE C. KLAR, OF HARTFORD, CONNECTICUT.

DESIGN FOR A PILLOW.

Application filed May 15, 1924. Serial No. 9,595. Term of patent 3½ years.

To all whom it may concern:

Be it known that I, KATHERINE C. KLAR, a citizen of the United States, and a resident of Hartford, in the county of Hartford and State of Connecticut, have invented a new, original, and ornamental Design for Pillows, of which the following is a specification, reference being had to the accompanying drawing, forming part thereof.

The figure is a face view of a pillow showing my new design.

I claim—

The ornamental design for a pillow, as shown.

KATHERINE C. KLAR.
